APPARATUS FOR ELEVATING OIL AND OTHER FLUIDS

Filed Oct. 27. 1926

FIG. 1

FIG. 2

FIG. 5

FIG. 6

FIG. 3

BY

INVENTOR.
LESTER H. MILES

ATTORNEY.

UNITED STATES PATENT OFFICE.

LESTER H. MILES, OF LOS ANGELES, CALIFORNIA.

APPARATUS FOR ELEVATING OIL AND OTHER FLUIDS.

Application filed October 27, 1926. Serial No. 144,597.

My invention relates to an apparatus for elevating fluid.

The general object of my invention is to provide an improved means whereby the oil 5 in a well may be brought to the surface when the gas pressure in the well is insufficient to cause the well to flow.

Another object of my invention is to provide an improved means which will increase 10 the flow of oil wells wherein the gas pressure is so weak that the oil barely flows.

A further object of my invention is to provide an apparatus, including a plurality of 15 stages for causing the removal of oil from wells.

Other objects of the invention will be apparent from the following description taken in connection with the accompanying drawings wherein:

20 Fig. 1 is a vertical section through an oil well showing my device mounted therein;

Fig. 2 is an enlarged vertical section through my device showing a number of the stages;

25 Fig. 3 is an enlarged vertical section through the adjustable check valve applied to the gas outlet pipe in Fig. 1;

Fig. 4 is an enlarged cross section through one of the check valve rings used in conjunction with my device;

Fig. 5 is a vertical section through the upper portion of an oil well showing means for forcing gas into the well, and

30 Fig. 6 is a fragmentary section of a modified form of my invention.

Referring to the drawings by reference characters I have shown my invention as comprising a number of stages 10, arranged in a tubing 11. The tubing is supported in 40 a casing head 12, which is provided with oil outlet pipes 13. The tubing 11 is surrounded by a casing 14 provided at its lower end, with the usual sections of perforated casing. The casing 14 is supported at its 45 upper end in the lower part of the casing head 12.

Each stage 10, of which there may be any desired number, consists of sections of inner tubing 15, having partitions 17 disposed 50 across the same. The sections 15 have ends adjacent partitions 18 which extend across

both the tubing 11 and the tubing 15 and are secured to the latter.

A single stage as shown, comprises two sections of the tubing 15, a lower section 19 and an upper section 20, the two combined extending from one partition 17 to the next partition 17. Intermediate the two sections 19 and 20 one of the partitions 18 is arranged. The lower end of the section 20 is provided 60 with ports 22 and the upper end of the tubing 19 is provided with similar ports 23.

Both of said sets of ports form communicating passages from the inside of the tubing sections 19 and 20 to a passage-way 24 formed by the adjacent portion of the tubing 15 and the adjacent portion of the tubing 11. The lower end of each section 19 is coupled to the upper end of the adjacent tubing 20 by a tubing joint 21.

70 The partitions 17 are shown as supported by clamping their outer peripheral edge between the top of the tubing 20 and the bottom of the tubing 19. The partitions 17 are provided with an internally threaded central 75 boss 25 into which pipes 26, having screw threaded ends, are fitted. The pipes 26 extend from the lower stage to the surface. The partitions 18 are supported by clamping their peripheral edges between the abutting 80 ends of the sections of the tubing 11 with tubing joints 11'.

The partitions 18 are provided with an internally threaded central boss 27 into which there is fitted an upwardly extending tubing 28 surrounding the pipe 26 and spaced therefrom, and a downwardly extending tubing 29 of the same diameter. The lower end of the downwardly extending tubing 29 is spaced from the top surface of the 90 partition 17 and the upwardly extending tubing 28 is spaced from the bottom surface of the preceding partition 17.

As stated the sectional pipe 26 extends from the bottom partition 17 of the first lift 95 upward to the surface and out through the casing head 12 and connects to another pipe 30 which has interposed in its length an adjustable check valve 31, see Fig. 3.

The first or lowermost stage 32 is not a 100 complete stage as previously described, merely corresponding to the upper half of

- the other stages. This stage 32 comprises a tubing section 33 externally threaded at its upper end for engagement with a tubing joint 21. The section 33 is internally 5 threaded at its lower end for engagement with threads formed on an upwardly dished base portion 34. Just above this base portion, the section 33 is provided with ports 35 which, like the ports 22 and 23, form a communicating passage from the inside of the tubing 33 to the passageway 24. The base 34 has a central internally threaded bore 36 into which is secured one of the tubing sections 28.
- 10 15 The base is also provided with an upwardly extending flange 37 internally threaded for engagement with screw threads formed on the lower end of the tubing 11. Over the outer peripheral edge of the base 20 34 is secured a packing ring 38 to prevent any passage of oil past the base other than through the central bore 36.

The operation of my device is as follows:

- The stages 10 are mounted in the tubing 11 25 as previously described, and the tubing is then lowered into the casing 14 until a number of stages are below the normal oil level in the well.

The oil and gas will enter through the 30 short tubing 28 shown at the bottom of Fig. 2, and on striking the bottom of the lowermost partition 17 will be directed downwardly against the top of the base 34. The oil will collect about the base 34 and some of 35 the gas will pass on up between the tubing 33 and the tubing 11 with but little oil being carried by the gas. As soon as the level of the oil on the base 34 reaches the top of the apertures 35 the gas will begin forcing the oil through these apertures 35 and into the 40 space between the tubing 33 and the tubing 11, and the height of the oil will rise until it reaches the bottom of the apertures 23 when it will pass through these apertures and fall 45 on the top of the partition 17 so that it will be trapped in a compartment, the bottom of which is formed by the partition 17. As the oil is forced up between the tubings 33 and 50 11, the gas also passes up between these tubings and it is the movement of this gas which carries the oil upwardly. The gas bubbles through the opening 35 and the lifting effect is due to the effect of the bubbles and their movement and pressure.

55 The level of the oil which falls on the partition 17 rises until the surface thereof touches the bottom of the tubing 29. The gas bubbles into the bottom of the tubing 29 carrying oil with it, this gas and oil passes 60 up through the tubing 28, strikes the bottom of the partition 17 and is deflected downwardly against the partition 18. This operation will be repeated until the top is reached and the oil flows off through the 65 pipes 13.

The excess gas passes upwardly through the pipe 26 and is released into storage tanks, not shown, by means of the pipe 30. The pressure of gas released being controlled by the adjustment of the valve 31.

70 It may at times be necessary to provide a check valve in the passageway 24 to prevent any backing up of the oil. And for this purpose I have illustrated a check valve ring 40 provided with a series of ball valves 41 as shown in Fig. 4, welded to the tubing 15 just above the outlet ports 35 and 22, and provided over its peripheral edge with a packing ring 42 to prevent any passage of the oil in the passageway 24 other than 80 through the valve 41. These check valve rings may be located to meet the particular requirements in each case.

85 In Figs. 5 and 6 I have shown a slight modification of my device for use in wells which do not contain enough gas for the operation of my device.

90 The stages are all constructed, assembled, and placed in an operative position in the well as in the first form except that I continue the pipe 26 downward past the base 34 for a distance and connect the surface end with a valve controlled pipe line 45 communicating with a pressure pump 46. The 95 pump 46 forces gas through the pipe 45 into the pipe 26 downwardly therein and is discharged into the oil at a point below the base 34. This gas in the oil assists to lift the oil in the well. The flow of oil in this modified form is the same as previously described in 100 the first form.

What I claim is:

1. In a fluid operated pump, a pair of spaced tubes comprising an inner and outer tube, means to divide said outer tube into a plurality of pumping compartments, means to divide said inner tube into a plurality of pumping compartments, and means to afford communication between said compartments, means for admitting the operating fluid and the liquid to the bottom compartment and means for discharging the pumped liquid from the top compartment.

105 110 115 120 125 2. In a device of the class described, a pair of spaced tubes comprising an inner and an outer tube, spaced partitions in said inner tube, other partitions spaced intermediate said first mentioned partitions and extending across said inner and outer tubes, said partitions forming a series of pumping compartments for the flow of the liquid, said other partitions supporting a tubing, said tubing extending above and below said other partitions and having opening ends, said inner tube having ports adjacent each face of the said other partitions, means for admitting liquid to the bottom compartment and means for discharging the pumped liquid from the top compartment.

130 3. In combination with a well containing

- a gaseous fluid, a casing in said well, an inner and outer tube in said casing, spaced partitions extending across said inner and outer tubes, said other partitions being supported by said outer tube, said other partitions supporting a tubing, said partitions forming a series of pumping compartments for the flow of the fluid, said tubing extending above and below said other partitions to points adjacent said first mentioned partitions and spaced therefrom, said inner tube having ports adjacent either face of the second mentioned partitions, said ports forming communicating passages from the interior of said inner tube to said outer tube, means for admitting fluid to the bottom compartment and means for discharging the pumped fluid from the top compartment.
4. In a device of the class described, a pair of spaced tubes including an inner and outer tube, spaced partitions in said inner tube, said partitions being supported by said partitions having a pipe running therethrough and supported thereby, other partitions spaced intermediate said first mentioned partitions and supported by said outer tube, said other partitions extending across said inner tube and said outer tube, said partitions forming a series of pumping compartments for the flow of the liquid, said pipe forming a continuous passageway from points below the first of said second mentioned partitions to the surface, a tubing supported by each of said second mentioned partitions, said tubing being around and spaced from said previously mentioned pipe, said tubing extending above and below each of said second mentioned partitions to points adjacent said first mentioned partitions and spaced therefrom, said inner tube having ports adjacent each face of the second mentioned partitions, said ports forming communicating passages from the interior of said inner tube to the space between said tubes means for admitting liquid to the bottom compartment and means for discharging the pumped liquid from the top compartment.
5. In combination with a well containing a gaseous fluid, a casing in said well, a tube in said casing, a second tubing in said first mentioned tubing and spaced therefrom to form a passageway, spaced partitions in said second mentioned tubing, said partitions being supported by said second mentioned tubing, said partitions having a pipe running therethrough and supported thereby, said pipe forming a continuous passageway from the first of said partitions to the surface, other partitions spaced intermediate said first mentioned partitions and supported by said first mentioned tubing, said partitions extending across said first mentioned tubing and said second mentioned tubing, said partitions forming a series of pumping compartments for the flow of the fluid, said tubing arranged around and spaced from said pipe and said last mentioned tubing ex-
- pumping compartments for the flow of the fluid, said other partitions supporting a tubing around and spaced from said previously mentioned pipe, said last mentioned tubing extending above and below said second mentioned partitions to points adjacent to but spaced from said first mentioned partitions, said second mentioned tube having ports adjacent each face of the second mentioned partitions, said ports forming communicating passages from the interior of said second mentioned tubing to the interior of said first mentioned tubing, means for admitting fluid to the bottom compartment and means for discharging the pumped fluid from the top compartment.
6. In combination with a well containing a gaseous fluid, a casing in said well, a tube in said casing, a second tubing in said first mentioned tubing and spaced therefrom to form a passageway, check valves in said passageway, spaced partitions in said last mentioned tubing, said partitions being supported by said second mentioned tubing, said partitions having a pipe running therethrough and supported thereby, said pipe forming a continuous passageway from the first of said partitions to the surface, other partitions spaced intermediate said first mentioned partitions and supported by said first mentioned tubing, said partitions forming a series of pumping compartments for the flow of the fluid, said partitions extending across said first mentioned tubing and said second mentioned tubing, said other partitions supporting a tubing around and spaced from said mentioned pipe, said tubing extending above and below said second mentioned partitions to points adjacent said first mentioned partitions and spaced therefrom, said second mentioned tubing having ports adjacent either face of the second mentioned partitions, said ports forming communicating passages from the interior of said second mentioned tubing to the interior of said first mentioned tubing, means for admitting fluid to the bottom compartment and means for discharging the pumped fluid from the top compartment.
7. In combination with a well containing a gaseous fluid, a casing in said well, an outer tubing in said casing, an inner tubing in said outer tubing and spaced therefrom to form a passageway, spaced partitions in said inner tubing, said partitions being supported by said tubing, said partitions having a pipe running therethrough and supported thereby, other partitions spaced intermediate said first mentioned partitions and supported by said outer tubing, said partitions forming a series of pumping compartments for the flow of the fluid, said other partitions extending across said inner and outer tubing, a tubing arranged around and spaced from said pipe and said last mentioned tubing ex-

tending above and below said second mentioned partitions to points adjacent said first mentioned partitions and spaced therefrom, said second mentioned tubing having ports forming communicating passages from the interior of said second mentioned tubing to the interior of said first mentioned tubing,

means for admitting fluid to the bottom compartment and means for discharging the pumped fluid from the top compartment.

10

In testimony whereof, I hereunto affix my signature.

LESTER H. MILES.
